UNITED STATES PATENT OFFICE.

FRANCIS S. CRAVEN, OF THE UNITED STATES NAVY.

BREECH-CLOSURE-OPERATING MECHANISM FOR GUNS.

1,113,416.

Specification of Letters Patent. Patented Oct. 13, 1914.

Application filed July 30, 1913. Serial No. 782,087.

To all whom it may concern:

Be it known that I, FRANCIS S. CRAVEN, ensign, United States Navy, a citizen of the United States, stationed on board the U. S. S. *Dixie*, have invented certain new and useful Improvements in Breech-Closure-Operating Mechanism for Guns; and I do hereby declare the following to be a full, clear, and exact description of the invention, such as will enable others skilled in the art to which it appertains to make and use the same.

The present invention relates to breech closure operating mechanism for guns, and has for its purpose to provide a means for opening and closing the breech of guns mounted in turrets which will give complete accessibility to the gun breech, and wherein the breech operations of one gun will offer no hindrance to the breech operations of an adjacent gun.

The further purpose of the invention is to provide a closure operating mechanism which is adaptable for opening and closing the breech with either a vertical or horizontal swinging movement, and which will automatically exert its maximum working force during the commencement of the unlocking and the finish of the locking movements of the breech block and with a decreased force and accelerated movement during the remainder of the unlocking and the commencement of the locking movements thereof.

With these and other objects in view the invention consists in the novel details of construction and combinations of parts more fully hereinafter disclosed and particularly pointed out in the claims.

Referring to the accompanying drawings forming a part of this specification in which like numerals designate like parts in all the views: Figure 1 is a side elevational view of a gun showing the application of the present invention. Fig. 2 is a similar view and showing the breech plug opened. Fig. 3 is a longitudinal sectional view of the gun breech and closure and showing the closure operating mechanism partly in elevation and partly in section. Fig. 4 is a rear elevational view thereof. Fig. 5 is a top plan view of the same; and Fig. 6 is a side elevational view of the breech plug closed and of the closure operating mechanism.

Referring to the construction in further detail, 1 designates the gun mounted on the support 2 through the medium of the sleeve

3, as in the usual manner. The breech closure employs the Welin or other interrupted screw type plug 4, designed after the usual manner and mounted on the plug carrier 5, 60 which is hinged to the gun breech at 6 as illustrated.

A series or compound wound motor 7 is suitably mounted on top of the gun sleeve 3 and has its axis disposed parallel with the axis of the bore of the gun barrel. The motor armature is mounted on a hollow shaft, or sleeve 8, which is suitably secured by end bearings on the motor casing. Passing through the armature shaft 8 is a shaft 70 9 having a feather and key-way connection 10 with said shaft, whereby to permit of axial translation of the drive shaft during the recoil and counterrecoil movements of the gun, but to effect rotation of said shaft 9 75 through the motor. In lieu of the feather and key-way connection, said shaft, where it passes through the sleeve 8, may be square or of such other design in cross section as will cause its rotation by the sleeve 8 but 80 permit of axial movement therethrough. The rear end of the shaft is mounted to rotate in the support 11, which also serves as a thrust bearing in both directions, mounted on the gun barrel, and is provided with a 85 screw-threaded section 12 engaging with a trunnioned nut 13 having a guide lug 14 which is adapted to travel on the guide rod 15 fixedly mounted on the supports 11 and 16. The rotation of the shaft 9 causes the 90 trunnioned nut 13 to be moved for operating the breech closure, as will now be explained.

A pair of pins 17 and 18 are mounted on the rear face 19 of the breech plug 4, and have engagement, respectively, with slotted cross heads 20 and 21 carried by the pair of parallel and vertically disposed rods 22 and 23. Said rods are mounted to have sliding movement in suitable guideways 24 and 25 of the plug carrier 5, and said plug carrier is hingedly mounted on the pin 6 (see Fig. 3). It will be evident that the reciprocating movements of the bars 22 and 23 will operate to lock or unlock the breech plug after the usual manner. In the upper ends of these bars are mounted pins 27 (see Figs. 3, 5 and 6), projecting toward each other and having engagement within the cam slots 28 and 29 of the cam plates or levers 30, which are pivotally mounted on the bar 31 secured to the lugs 32 on the plug carrier. The cam slot and pin engagements (27 and

29) just referred to, are operable to effect the locking and unlocking movements of the bars 22 and 23, as above described. A pair of drag links 33 pivotally connect the cam plates 30, by the pivot pin 34, to the traveling nut 13 on the drive shaft 9, whereby to actuate said cam plates for the locking and unlocking movements of the breech plug, and the opening and closing swinging movements of the plug carrier 25. The pivot pin connection 34, between the drag links and the cam plates, is provided with a sleeve 35 which serves as a spacing member for said links, and a tie rod 36 is secured 10 to said links and is similarly provided with a sleeve or spreader 37.

There is a safety catch to prevent premature rotation of the plug for closing. It is of the usual plunger type, half of which 20 enters a slot in the side of the plug as the plug leaves its closed position, but which is forced back into the plug carrier by contact with the rear face of the gun as the plug closes, freeing the plug in rotation. It is 25 shown by 38.

The cam slots of the levers 30 are disposed to the end that their initial movement, in the opening of the breech, will exert its maximum working force to unlock the 30 breech plug, and the further movement will be of decreased force but at accelerated speed, and on the closing of the breech this operation is reversed.

The operation of the mechanism is as follows:—The rotation of the drive shaft 9 by the motor 7 causes the trunnioned nut 13 to be fed by the screw 12, and the cam plates 30 are turned on their pivot pin 31 by the drag link connections 33. The initial movement of said cam plates, in opening the breech, is on the pivot pin 31, and the pin and cam slot engagements (27, 28 and 29) 40 actuate the bars 22 and 23 to unlock the breech plug. And when said pin and slot 45 engagements have reached their limit of movement the continued movement of the drive links transfers the point of fulcrum from the pivot pin 31 to the pivot pin 6 of the breech plug carrier 5. The parts then 50 have the position shown in broken lines in Fig. 1, and said plug carrier begins its opening swinging movement the completion of which brings the breech plug to the position shown in Fig. 2.

55 It is obvious that those skilled in the art may vary the details of construction and arrangement of parts without departing from the spirit of my invention, and therefore I do not wish to be limited to such features 60 except as may be required by the claims.

I claim:

1. The combination with a gun having a breech closure and carrier therefor, of members connected to the closure; levers fulcrumed on the carrier operatively connected 65

to said members; a motor fixedly mounted relative to the gun; and operative connections between said levers and the motor whereby to actuate said closure and the carrier.

2. The combination with a gun having a breech closure and a carrier therefor, of members connected to the closure; levers fulcrumed on the carrier operatively connected to said members; an actuating mechanism 70 fixedly mounted relative to the gun; and operative connections between said actuating mechanism and said levers whereby to actuate said closure and the carrier.

3. The combination with a gun having a breech closure and a carrier therefor, of members connected to the closure; levers fulcrumed on the carrier operatively connected to said members; a motor fixedly mounted relative to the gun; a shaft connected to be 80 driven by the motor; and operative connections between said shaft and said levers whereby to actuate said closure and the carrier.

4. The combination with a gun having a breech closure and a carrier therefor, of members connected to the closure; levers fulcrumed on the carrier operatively connected to said members; a motor fixedly mounted relative to the gun; a shaft connected to be 90 driven by the motor; a member connected to be driven by said shaft; and operative connections between said driven member and said levers whereby to actuate said closure and the carrier.

5. The combination with a gun having a breech plug and a swinging breech plug carrier, of members mounted to move on said plug carrier and connected to said breech plug; levers fulcrumed on said plug carrier 105 and connected to actuate said plug connecting members; a motor; and operative connections between said motor and said levers to lock and unlock the breech plug and swing the breech plug carrier.

6. The combination with a gun having a breech plug and a swinging breech plug carrier, of a pair of bars slidably mounted on said plug carrier and pivotally connected to said breech plug; a pair of levers pivotally mounted on said plug carrier and having cam slot engagement with said slidable bars to actuate the latter; a motor; a member connected to be driven by the motor, and link connections between said driven member and said pivoted levers operable to lock and unlock the breech plug and swing the breech plug carrier.

7. The combination with a gun having a breech plug and a swinging breech plug carrier, of a pair of bars slidably mounted on said plug carrier and pivotally connected to said breech plug; levers pivotally mounted on said plug carrier and having oppositely disposed cam slots; pins mounted on said 120 125 130

slidable bars engaging with said cam slots to actuate said bars; a motor; a screw shaft connected to be driven by the motor; a member connected to be driven by said screw shaft; and link connections between said driven member and said pivoted levers operable to lock and unlock the breech plug and swing the breech plug carrier.

8. The combination with a gun having a breech plug and a swinging breech plug carrier, of a pair of bars slidably mounted on said plug carrier having pivotal connections with the breech plug; a pair of levers pivotally mounted on the plug carrier and provided with oppositely disposed cam slots; pins carried by said slidable bars and engaging with said cam slots to actuate said bars; a motor; a screw shaft connected to be rotated by the motor; a trunnioned nut mounted to travel on said screw shaft; and a pair of drag links connecting said trunnioned nut with said cam slotted levers operable to lock and unlock the breech plug and swing the breech plug carrier.
- 25 9. The combination with a gun having a breech plug and a swinging breech plug carrier, of a pair of bars slidably mounted on said plug carrier having pivotal connections with the breech plug; a pair of levers pivotally mounted on the plug carrier and provided with oppositely disposed cam slots; pins carried by said slidable bars and engaging with said cam slots to actuate said bars; a motor fixedly mounted relative to the gun; 35 a screw shaft mounted on the gun connected

to be rotated by the motor and having independent axial translation; a trunnioned nut mounted to travel on the gun and having screw engagement with said shaft; and a pair of drag links connecting said trunnioned nut with said cam slotted levers operable to lock and unlock the breech plug and swing the breech plug carrier.

10. The combination with a gun mounted in a sleeve and having a breech plug and a swinging breech plug carrier; of a pair of bars mounted to slide on said carrier; pins mounted on the breech plug; slotted heads carried by said slidable bars having engagement with said pins; a pair of levers pivotally mounted on the plug carrier and having cam slots; pins carried by said slidable bars engaging with said cam slots to actuate said slidable bars; a motor mounted on the gun sleeve; a screw shaft mounted on the gun and connected to be rotated by the motor and having independent axial translation; a trunnioned nut mounted on the gun and having driving engagement with said screw shaft; and a pair of drag links connecting said trunnioned nut with said cam slotted levers operable to lock and unlock the breech plug and swing the breech plug carrier.

In testimony whereof, I affix my signature, in presence of two witnesses.

FRANCIS S. CRAVEN.
